Atty.

UNITED STATES PATENT OFFICE.

MAX BUCHHOLZ, OF CASSEL, GERMANY.

PROTECTION OF ELECTRIC APPARATUS.

Application filed June 28, 1927, Serial No. 202,143, and in Germany July 1, 1926.

My invention refers to electrical apparatus of all kinds and more especially to means whereby such apparatus can be protected against partial or total destruction by overloads caused by excess currents, short circuits and the like. It is an object of my invention to provide means whereby the detrimental effect of such overloading of current carrying parts is prevented from influencing such parts either by cutting same out before any injury has been done them or by setting some annunciating device in operation to warn the attendant.

As is well known to those skilled in the art, when electrical transformers, switches or other electrical apparatus are overloaded by short circuits, excess currents and the like, the current carrying parts will be unduly heated, and if insulating means are provided adjoining such parts, vapours or gases of decomposition of the solid or fluid insulating means will be developed after some time around the current carrying parts. It is equally known that these gases or vapours are more dangerous even than air bubbles, inasmuch as they embody finely distributed solid products of decomposition, such as for instance soot, which are conductive and are therefore liable to create leakage paths and the like. For practical reasons an exhausting of the gases thus formed is frequently impossible and such step would only constitute an imperfect remedy inasmuch as the solid products of decomposition would not be exhausted along with the gases. In consequence of these circumstances the insulation of the current carrying parts will gradually be diminished in value and it is therefore imperative to prevent gases or vapours of decomposition from being developed. In other words, provision must be made for preventing the current carrying parts and their insulation from being overloaded so as to prevent at the same time the decomposition of the insulating means.

According to the present invention this is attained by a protective system comprising a protective conductor electrically connected with the current carrying parts to be protected, either in parallel or in series or in mixed connection, this protective conductor being arranged or formed in such manner as to have its temperature changed by an overload, which may occur in the system, before

the temperature of the current carrying parts to be protected is changed. The temperature of the said protective conductor will therefore also overstep at an earlier moment the limit at which a decomposition of the surrounding solid or liquid insulating material or the formation of gases or vapors from this material begins. Therefore, if the protective conductor is subjected to an overload, gas or vapor bubbles will be developed in the insulating material in contact with the said conductor, before such development can take place at the other current carrying parts, and these gas or vapor bubbles will operate a protective device provided for this purpose, which may be a mechanical or electrical interrupting device or some annunciating device or alarm, thereby providing that the current carrying part is cut out before any harm is done. According to my invention I cause the protective conductor to cooperate with fluid or solid media surrounding same, for instance with the insulating liquid such as oil, carbon tetrachloride or the like or with solid insulating means in such manner that the gases or vapors developed from such media, either by evaporation or by decomposition, brought about by the rise of temperature in the conductor, are caused to act on the electrical or mechanical protective device provided for this purpose so as to either cut out the part to be protected or to actuate a mechanical or electrical annunciating device.

In the drawings affixed to this specification and forming part thereof two arrangements embodying my invention are illustrated diagrammatically by way of example, Fig. 1 being a vertical section of a three-phase transformer provided with protective means embodying my invention, while Fig. 2 shows the invention as applied to a cable or bus bar.

Referring first to Fig. 1, *a* is the transformer tank filled with an insulating liquid such as oil, *b* is the compensating tank and *c* is the pipe connecting same. The three phases *d*¹, *d*², *d*³, extend through inlet bushes *e*¹, *e*², *e*³, into the tank *a* and are connected to the three transformer coils *f*¹, *f*², *f*³. In order now to prevent gases or vapors of decomposition of the oil or other insulating medium to be formed at the coils *f*¹, *f*², *f*³, in the case of an overload in the system, a protective conductor *g* is inserted between the inlet bush *e*² of the phase *d*² and the coil *f*². In the modi-

ification illustrated in the drawing, this protective conductor has a helical form and can for instance consist of solid copper wire of circular cross section, this section being somewhat smaller than the cross section of the copper wires in the coils. In consequence of this difference in cross section, when an overload arises in this system, the protective conductor *g* will suffer a rise of temperature before the coils themselves are heated up, and therefore the oil adjoining the conductor *g* will be decomposed before any inadmissible overloading of the other current carrying parts or of the insulating means adjoining them has taken place. In consequence of this decomposition of the oil surrounding the conductor *g*, gas or vapour bubbles will be formed and these bubbles shall now be used for operating a protective device substantially in the manner described in my co-pending application for patent of the United States, filed September 15, 1922, Serial No. 488,457 and the divisional applications resulting therefrom. To this end some suitable protective device, for instance a contact of a protective circuit may be disposed in the case *h* inserted in the pipe *c* leading from the transformer tank *a* to the compensating vessel *b*, this contact being operated either by an excess pressure caused by the gases developed in the oil or by the buoyancy effect of these gases, as they rise in the liquid and in the pipe *c* or by their catalytic action or by other causes. The contact being thus actuated by the gases developed at *g* will then either cut out the transformer altogether or will operate an annunciating device, for instance an alarm, forming part of the protective circuit.

Obviously the formation of gases or vapours at the transformer coils themselves is altogether prevented and there is no need for employing the well known complicated overload relays and the like.

If desired, the protective conductor, such as *g*, can be surrounded by heat insulator, such as for instance paper, cotton, asbestos or the like, in order to better utilize the rise of temperature in this conductor and to accelerate the formation of gases.

I may also use a protective conductor consisting of a material which is heated up more quickly than the material forming part of the other current carrying parts, thereby causing the formation of vapours or gaseous products of decomposition in the medium surrounding the protective conductor, before the other current carrying parts are affected.

In the manner described with reference to a transformer also all other electrical devices and apparatus can be protected, such as switches, generators, motors, cables, bus bars and the like.

In Fig. 2 a cable embodying my invention is illustrated. *i* is the electrical conductor

forming part of the cable and *k* is the insulation surrounding same. *i'* is a protective conductor of smaller cross section than the cable conductor which is inserted in the same and is enclosed in an asbestos envelope *l*, the whole being surrounded by a fluid insulating medium, for instance oil, contained in a sleeve *m*. The sleeve *m* has T-shape, an extension *o* being formed thereon, in which is mounted an electrical contact device forming part of a protective circuit and having the form of a plate-shaped lever *p* pivoted to the wall of the extension *o* for free rocking motion in vertical direction. Whenever an overload occurs in the cable, the insulation *k* and the oil surrounding the protective conductor *i'* will be decomposed long before the cable conductor *i* is unduly overloaded and the gas bubbles formed at *i'* will rise in the oil and in collecting below the rocking plate *p* will lift same so as to close the contact and the protective circuit.

The term "protective device" as used in the claims here annexed is to be understood to include mechanical as well as electrical means for automatically cutting out the system to be protected or for operating an annunciating device of some suitable kind.

I wish it to be understood that I do not desire to be limited to the exact details of construction shown and described for obvious modifications will occur to a person skilled in the art.

I claim:

1. Protective system for electrical devices comprising a current carrying part, a protective conductor electrically connected with said part, a non-gaseous insulator in contact with said conductor, said conductor being adapted to have its physical condition changed before the physical condition of said part is changed, and a protective device adapted to be set operating by products of decomposition from said insulator developed in consequence of such change in said conductor, for varying the operative condition of said protective device.

2. Protective system for electrical devices comprising a current carrying part, a protective conductor electrically connected with said part, non-gaseous insulating means decomposable by heat in contact with said conductor, said conductor being adapted to have its temperature changed before the temperature of said part is changed, and a protective device adapted to be set operating by products of decomposition from said insulating means developed in consequence of such change in said conductor, for varying the operative condition of said protective device.

3. Protective system for electrical devices comprising a current carrying part, a protective conductor electrically connected with said part, non-gaseous insulating means decomposable by heat in contact with said con-

ductor, said conductor being adapted to have its temperature changed before the temperature of said part is changed, a protective circuit and a contact in said circuit adapted to be operated by products of decomposition of said insulating means.

4. Protective system for electrical devices comprising a current carrying part, a conductor of smaller cross-sectional area inserted in said part, non-gaseous insulating medium in contact with said conductor, a protective circuit and a contact forming part of said circuit and adapted to be actuated by products of said circuit and adapted to be actuated by

the products resulting from a rise of temperature in said insulating medium.

5. Protective system for electrical devices comprising a current carrying part, a conductor of smaller cross-sectional area inserted in said part, non-gaseous insulating medium in contact with said conductor, a protective circuit and a contact forming part of said circuit and adapted to be actuated by products of heat decomposition of said insulating medium.

In testimony whereof I affix my signature
MAX BUCHHOLZ.
